Primary Examiner—Robert M. Spear*(74) Attorney, Agent, or Firm*—Connolly Bove Lodge & Hutz LLP(57) **CLAIM**

The ornamental design for paper toweling, as shown and described.

DESCRIPTION

FIG. 1 is a plan view of a paper toweling showing my new design; and,

FIG. 2 is a plan view of a second embodiment of my new design.

The surfaces or portions of the article not shown in the drawing or described in the specification form no part of the claimed design.
